(57) **CLAIM**

The ornamental design for a combined aroma diffuser and humidifier with wireless speaker, as shown and described.

DESCRIPTION

FIG. 1 is a first perspective view of a combined aroma diffuser and humidifier with wireless speaker showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion 9 in FIG. 2.

The evenly spaced broken lines depict portions of the combined aroma diffuser and humidifier with wireless speaker that form no part of the claimed design. The dot dash dot broken lines denote the boundaries of the detail areas and form no part of the claim.
